ORTHOPEDIC FOOTWEAR

Nathan V. Levitt, New York, N. Y.

Application December 9, 1939, Serial No. 308,332

1 Claim. (Cl. 36—76)

This invention relates to orthopedic footwear appliances or corrective means to be either inserted inside the shoe or incorporated in the fabrication of the shoe, for the purposes of correcting common foot ailments. One embodiment of my invention is shown in the accompanying drawing wherein:

Fig. 1 is a longitudinal section through a shoe incorporating my improvement and showing the bones of the foot; Fig. 2 is a plan view, with my corrective device in place and also showing the bones of the foot; Figs. 3-6 are partial sections taken on lines 3—3, 4—4, 5—5 and 6—6, respectively, of Fig. 1; Fig. 7 is a perspective view of the insert; and Fig. 8 is a modified form of the invention.

The human foot has, as is well known, four important arches; two of them extending in a longitudinal direction and two in a direction transverse thereto. The longitudinal arches are the inner longitudinal arch, which is shown in Fig. 2 generally in the direction of the line IA—IA, and the outer longitudinal arch, which is shown in Fig. 2, generally in the direction of the line OA—OA. The inner arch (IA—IA) extends from the astragalus bone 10 to the first, second and third metatarsals 11, 12 and 13, crossing the scaphoid 16 and the external, middle and internal cuneiform bone respectively 21, 22 and 23. The outer longitudinal arch (OA—OA) extends from the os calcis (or heel bone) 20 to the fourth and fifth metatarsals 14 and 15 respectively, crossing the cuboid bone 24.

Common foot ailments are caused by "fallen arches," by which is meant a breaking down of the outer longitudinal arch. It has long been the practice to prevent fallen arches or to support them after they have broken down, by the use of arch supports, either as separate inserts or incorporated in the shoe, positioned along the inner edge of the foot and underlying the inner longitudinal arch (IA) or instep. It has been thought that the supporting of the inner arch— which is the more prominent of the pair of longitudinal arches and extends over a greater portion of the foot, that is, comprises more bones, as will be readily seen from Fig. 2—would be sufficient to maintain the foot against a breaking down in a longitudinal direction. I have found, however, that while it might seem that the inner longitudinal arch, or rather the breaking down thereof, is the main cause of many of the common foot ailments, it is really the hitherto unnoticed outer longitudinal arch which is at the root of the common foot ailments. I have

further discovered that by providing a suitable support for the outer longitudinal arch (as will be explained and shown below), the breakdown of this arch is prevented and also some support is given to the longitudinal arch.

The importance of supporting the outer longitudinal arch will be seen from an analysis of the process of walking and from a consideration of a very common foot ailment known as "Morton's toe." Walking is a "three point process," by which is meant that the foot is not placed on the ground with all points in simultaneous contact therewith, but rather three different points or parts of the foot contact the ground in sequence; the first point of contact is the os calcis or heel bone, which is followed by the portion of the foot along the fifth metatarsal or outer edge of the foot, the third and last point of contact is at the sesamoid bone (not shown) which is at the distal end of the first metatarsal. It is thus seen that the entire weight of the body is first thrown on the outer edge of the foot or along the outer longitudinal arch which comprises the first two points of the "tripod," namely, the os calcis contact and the fifth metatarsal contact above referred to. Hence the vital importance of providing a suitable support for the outer longitudinal arch becomes evident.

The further need for such a support is seen from consideration of the ailment known as Morton's toe, which is a disturbance caused by the cramping of the fourth metatarsal (14, Fig. 2) due, for one thing, to the fact that there is not ample support for this bone. It is seen from Fig. 2 that both the fourth and fifth metatarsals must share together whatever support they get from the cuboid bone (24). On the other hand, the first, second and third metatarsals, each have a separate supporting bone, respectively, the external, middle and internal cuneiform bones (21, 22 and 23). Hence, by providing a suitable support along the outer longitudinal arch as will be seen, further and sufficient support is afforded for the fourth metatarsal, to remedy Morton's toe ailment.

In the use of "arch supports," by which is meant supports for the inner longitudinal arch, there is more than sufficient room for positioning such appliances at the inner edge of the shoe and underlying the instep of the foot. When it comes to providing a suitable support for the outer longitudinal arch, on the other hand, there is very little room or clearance for such a support, as will be readily seen from Fig. 1, wherein it appears that the portions of the bone

structure which constitute the outer longitudinal arch, namely, the lower portions of the os calcis bone 20, the cuboid bone 24 and the fifth metatarsal 15, are in direct contact with the shoe; these points of contact are indicated in Fig. 1 by letters *a* and *b* (os calcis), *c* (cuboid) and *d* (proximal end of the fifth metatarsal). The difficulty of positioning a suitable support for the outer longitudinal arch is readily seen by examining an ordinary shoe. It will be seen that the bottom of the foot lies closely against the insole of the shoe and, in fact, extends or bulges somewhat beyond, that is, outwardly of the sole of the shoe.

15 In Fig. 1 the insole of the shoe is designated 1 and the outer sole is designated 2, the heel being indicated at 3. I have discovered that a satisfactory support for the outer longitudinal arch is afforded by inserting a strip of material, preferably of leather, which is designated generally as 5 (shown in perspective in Fig. 7) to underlie the outer sole 2 and extending from the beginning of the instep 2a to the heel 3. Where the portion of the insert 5 extends beyond the instep and between the sole 2 and the heel 3, one or more of the heel lifts, or rather portions thereof, may be the first removed.

20 It will be seen best from Fig. 1, that the thickest point of the insert is in the vicinity underlying the juncture between the proximal end of the fifth metatarsal 15 and the cuboid 24. The insert tapers down or "feathers" in thickness to the edges thereof; that is, the material tapers both in a longitudinal direction and also in a transverse direction. The effect of this feathering is also shown in the sectional views of Figs. 3-6 which are taken at different points along the longitudinal axis, Fig. 1.

25 It is understood that the outer longitudinal arch insert of my invention may be used alone or in conjunction with the usual "arch support" for the inner longitudinal arch.

30 In Fig. 1 the insert portion is positioned to underlie the outer sole 2. The insert, however, if desired, may be placed above the sole of the

shoe as shown in Fig. 8, where the insert, in other respects like that shown above, is designated 15.

35 My invention not only remedies the foot ailments above noted, but also, and as a result thereof, causes persons to walk with an "inversion" aspect, and not with an "eversion" aspect. Most people, especially those having foot ailments, walk with the toes of their feet pointed outwardly—this is known professionally as "eversion." By providing a support or raised portion at the outer borders of the shoe as explained above, the foot is caused to be turned inwardly, i. e., to assume the desired "inversion" aspect.

40 Incidental to the "inversion" corrective measures of my invention, there is a marked improvement in the evenness of foot or rather shoe pressure on the ground, which results in a more even wearing of the shoe material; this is especially noticeable with respect to rubber heels which last 20 very much longer.

I claim:

45 A corrective device for a human foot which comprises a supporting means for the outer longitudinal arch of the foot, extending from the os calcis to the distal ends of the metatarsal and underlying the cuboid, said means comprising a strip of leather positioned outside the shoe in underlying relation to the outer sole thereof between the beginning of the instep to a point within the heel of the shoe, portions of the heel of the shoe being removed to receive the heel portion of the said strip, the said strip extending from the outer edge of the shoe to a longitudinal line at the internal cuneiform bone, the thickest 30 point of the said strip being at the outer edge underlying the juncture between the proximal end of the fifth metatarsal and the cuboid, the strip gradually tapering from the said high point transversely to the said longitudinal line and 35 gradually tapering from the said point longitudinally to its said forward end at the instep and to its said rearward end at the heel.
